[57] **CLAIM**

The ornamental design for a combined wringer handle grip, tubular shell, and collar for a mop, as shown and described.

DESCRIPTION

FIG. 1 is a top, front, and left-side perspective view of a combined wringer hand grip, tubular shell, and collar for a mop showing our new design;

FIG. 2 is a front elevational view thereof, the rear and side elevational views being identical;

FIG. 3 is a top plan view of the wringer hand grip;

FIG. 4 is a top plan view of the tubular shell;

FIG. 5 is a top plan view of the collar; and,

FIG. 6 is an elevational view of the entirety of the wringer hand grip.

The wringer hand grip, the tubular shell, and the collar are shown individually in FIGS. 3, 4, 5, and 6 for convenience of illustration.

The handle and mop head are shown in broken lines for illustrative purposes only and form no part of the claimed design.
